VEGETABLE CUTTING DEVICE

Filed April 22, 1931

INVENTOR.

Mabel White

BY

Glenn L. Fish

ATTORNEY.

UNITED STATES PATENT OFFICE

MABEL WHITE, OF SPOKANE, WASHINGTON

VEGETABLE CUTTING DEVICE

Application filed April 22, 1931. Serial No. 531,911.

My invention relates to vegetable cutting devices and certain objects of the invention are to provide a device for use in cutting vegetables into cubes and comprising stationary 5 transversely disposed blades and a vertically movable blade. Other objects are to provide means whereby the cutting movement of the vertical blade is eliminated and whereby the vegetables are cut into rectangular 10 strips only. Further objects are to provide adjustable means whereby the device is adapted to cut vegetables into cubes of various sizes.

With the above and other objects in view 15 which will appear as the description proceeds, the invention consists of the novel construction, adaptation, combination and arrangement of parts hereinafter described and claimed. These objects are accomplished by 20 devices illustrated in the accompanying drawing; wherein:

Figure 1 is a top plan view of the device;

Fig. 2 is a view in longitudinal vertical section taken substantially on a broken line 2, 25 2 of Fig. 1;

Fig. 3 is a fragmentary detail view in perspective showing the stationary and movable blades mounted in channel guides;

Fig. 4 is a view in perspective of one of the 30 multiple blade cutting members; and

Fig. 5 is a view in perspective of the front end of the device.

Referring to the drawing wherein like reference numerals indicate like parts, the numeral 5 designates a rectangular container provided on one side with an upstanding lug bearing 6. A bell crank lever 7 is fulcrumed to said lug bearing and the short arm of said bell crank has its end pivotally connected to 40 a link member 8 extending rearwardly and exteriorly of the container. The rear end of said link member is bifurcated to receive a pawl lever 9 and said pawl lever is pivotally and adjustably connected to said link member 45 by a pin 10 passing through holes in the link and lever. A plurality of holes 11 is provided in said pawl lever whereby the link member may be adjustably connected thereto by shifting said pin to the different holes 50 as will be understood.

The pawl lever 9 is fulcrumed on a shaft 12 that is mounted in bracket bearings 13 fixed to the rear exterior end of the container 5. The lower end of said pawl lever has a rod 14 fixed thereto in parallel relation with 55 said shaft and its outer end has a pawl 15 pivotally mounted thereon and disposed centrally of the rear end of the container. The outer extended end of said pawl is formed into a finger rest 16 and a spring 17 normally retains the inner end of the pawl in engagement with the teeth of a rack bar 18. Said rack bar extends slidably through a bearing 19 and centrally into the container and its inner end is fixed to a plunger 20 that is slidably disposed within and transversely of said container. 60

Referring to Fig. 2 of the drawing, when the long arm of the bell crank lever 7 is moved downward to the dotted position its short 70 arm will pivotally draw the link member 8 and the upper portion of the pawl lever 9 forward to the dotted position and the lower portion of said pawl lever with its rod 14 will carry the pawl 15 backward to the dotted position. When the long arm portion of said bell crank is again pivotally raised to the full line position said pawl will slidably move the rack bar 18 and plunger 20 75 forward. Thus it will be obvious that said plunger may be moved to the forward end of the container by repeating said movement. By holding down on the finger rest 16 the pawl is released from engagement with the rack bar and the plunger may be moved entirely to the rear end of the container. A spring 21 fixed to the short arm of the bell crank and to the container helps to raise the long arm of the bell crank to its normal position. 80

The forward end of the container 5 is open and has an upstanding channel guide member 22 fixed to either side thereof and the lower portions of said guides are adapted to retain a pair of stationary multiple blade cutting members designated respectively as a whole by the numerals 23 and 24. Said cutting members are each the same in construction and, as shown in Fig. 4, comprise a pair of supporting frames 25 retained in adjust- 85 90 95 100

able spaced apart relation by bolts 26 each having opposing screw threads on their respective ends. Said frame members are each provided with corresponding spaced apart 5 tongues 27 having a pin 28 disposed therethrough. Said pins support a plurality of cutting blades 29 in spaced apart relation. Referring to Fig. 2, one of said multiple blade cutting members is placed in the lower portion 10 of the channel guides with its blades in the horizontal position and the other with its blades in the vertical position. It will thus be apparent that said blades will cut a vegetable into rectangular strips when placed between the plunger 20 and said blades and forced through the blades by the aforesaid rack and pawl means.

A movable cutting blade 30 is slidably disposed in the channel guides 22 in front of the 20 stationary cutting members 23 and 24. Said blade is normally retained in the raised position by a spring 31 having its lower end mounted in a tubular portion 32 of one of said channel guides and its upper end bearing 25 against a shoulder 33 fixed to said blade. As shown in detail in Fig. 3, said blade is held in resilient slidable engagement with the multiple blade cutting member 23 by a leaf spring 34 fixed to said blade and bearing against the 30 inside of the channel guide, and said spring allows the movable cutting blade to be forced outwardly from the stationary cutting blades by the strips of vegetable on the upward movement as will be understood.

35. The long arm portion of the bell crank lever 7 is offset at 35 to bring its handle end portion 36 in a central position with respect to the container 5. Said handle portion registers with a vertical slot 37 in the cutting blade 30 and is itself provided with a slot 38. Lugs 39 are disposed at the upper end of said vertical slot and pin 40, passing through said lugs and through the handle slot, pivotally and slidably connect said cutting blade to said handle and bell crank lever.

As hereinbefore set forth, each upward movement of the bell crank lever 7 causes the pawl to push the plunger 20 toward the cutting blades and the springs 21 and 31 assist 50 in said upward movement. A vegetable placed within the container 5 in front of said plunger may thus be forced through the transversely disposed stationary blades and cut into rectangular strips. At each downward 55 movement of the bell crank and the handle 36 said pawl is moved back to a retracted position and hold on the teeth of the rack bar 18 and the cutting blade 30 cuts off equal portions of the rectangular vegetable strips. By 60 shifting the pin 10 and the link member 8 to different holes 11 in the pawl lever 9 and by eliminating certain of the stationary blades 29 the blades are made to cut a vegetable into cubes of different sizes, and by removing the 65 pin 40 the bell crank moves up and down in

the slot 37 leaving the blade 30 in the raised position whereby the vegetable will be cut into rectangular strips only.

Having thus described my invention, it being understood that minor changes may be resorted to in its construction and arrangement without departing from the scope and spirit of the invention, what I claim and desire to secure by Letters Patent of the United States is:—

1. A vegetable cutting device having in combination a container open at one end, upstanding channel guides for said end, stationary blades mounted in said guides in transverse arrangement across said open container end, a cutting blade mounted for vertical movement in the guides across the front face of the stationary blades and having a central vertical slot, a spring fixed to said cutting blade whereby same is adapted to be moved away from the stationary blades, another spring for one of the guides adapted to retain said cutting blade in a normally raised position, a plunger for the container, a rack bar connected to the plunger and extending slidably through the rear end thereof, a pawl engaging the rack bar, means for releasing the pawl from engagement with the rack bar, a rod and pawl lever for actuating the pawl, a link member detachably and adjustably connected to the pawl lever, a bell crank lever fulcrumed to the container and pivotally connected to the link member, a spring adapted to retain the long arm of the bell crank in a normally raised position, a forward offset handle end portion for the long bell crank arm pivotally and slidably connected to the movable cutting blade and within its vertical slot whereby upward movement of the handle raises said blade and causes the plunger to move forward a predetermined distance and whereby downward movement of the handle and cutting blade causes the pawl to take a retracted hold on the rack bar, and said bell crank handle portion adapted to be disconnected from the movable cutting blade whereby said blade remains stationary in the raised position and said handle portion is adapted to move up and down in the vertical slot of said movable blade.

2. A vegetable cutting device having in combination a container open at one end, upstanding channel guides for said end, stationary blades mounted in said guides in transverse arrangement across said open container end, a cutting blade mounted in the guides for vertical movement across the front face of the stationary blades and having a central vertical slot, a spring fixed to said cutting blade whereby same is adapted to be moved away from the stationary blades, another spring for one of the channel guides adapted to retain said cutting blade in the normally raised position, a plunger for the container, a rack bar connected to the plunger and ex- 120 125 130

tending slidably through the rear end thereof, a pawl engaging the rack bar, a pawl lever for actuating the pawl, a link member detachably and adjustably connected to the pawl lever, a bell crank lever fulcrumed to the container and pivotally connected to the link member, a forward offset handle end portion for the bell crank pivotally and slidably connected to the movable cutting blade whereby upward movement of the handle raises said blade and causes the plunger to move forward and whereby downward movement of the handle and cutting blade causes the pawl to take a retracted hold on the rack bar.

15 In testimony whereof I affix my signature.
MABEL WHITE.
